ATTORNEY.

UNITED STATES PATENT OFFICE.

ALBERT S. ALOE, OF ST. LOUIS, MISSOURI, ASSIGNOR TO A. S. ALOE COMPANY, OF ST. LOUIS, MISSOURI, A CORPORATION OF MISSOURI.

ADVERTISING DEVICE.

Application filed August 7, 1922. Serial No. 580,114.

To all whom it may concern:

Be it known that I, ALBERT S. ALOE, a citizen of the United States, residing at the city of St. Louis, in the State of Missouri, have invented certain new and useful Improvements in Advertising Devices, of which the following is a specification.

The object of this invention is to provide means for the life-like demonstration of the uses and appearance of various kinds of eyeglasses and the like. Any kind or style of such glasses can be exhibited in this way.

In the accompanying drawing forming part of this specification, in which like numbers of reference denote like parts wherever they occur,

Figure 1 is a front elevation, and

Figure 2 is a vertical sectional view, taken on the line 2—2 in Figure 1.

20 The shadow box 1 is lined with velvet or other suitable background material 2. The back 3 is so located as to leave a hollow space between it and the flange 4, which hollow is of sufficient depth to receive the 25 pedestal 5 and figure 6, so that the flush line of the front of the flange 4 is forward of the nose of the figure 6. The flange 4 is in the form of a flat square member attached to the box 1. Toward the back 3 of the box 30 slope the four sides 7, to the edges 8 of which the flange 4 is attached.

The flange 4 projects toward the figure 6 a sufficient distance to cover lamps 9, of which a row or plurality of rows is arranged 35 within the box and behind the flange 4 to a greater or less extent of the entire length or circuit of the flange 4. The wire 10 furnishes the electricity to the lamps 9. A storage battery or a dry-cell battery may be 40 used if electricity from a line is not available. A stud 11 projects upwardly from the pedestal 5 and enters a corresponding hole in the base of the figure 6. This holds the figure 6 in place on the pedestal, but 45 permits the same to be turned at any angle, so as to allow the natural or artificial light to fall in any desired manner and to produce the best effects in chiar-oscuro. The head 12 of the figure 6 is preferably attached to 50 the neck 13 by a stud 14, for the same reasons.

The head 12 is preferably made of wax, in order to be more lifelike. This is true, also, of the neck 13 and the bust of figure 6. 55 The hair 15 may be natural.

The glasses 16 are positioned on the nose and in front of the eyes as in life and may be hornrimmed (as shown in the drawing) and provided with temple pieces 17 (as shown in the drawing) or may be minus the 60 temple pieces 17 or rimless as may be desired.

The figure 6, besides wearing any desired kind of glasses, will preferably be dressed. In actual use it has been found that when provided with a hat and the upper part of a dress or suit and appropriate neckwear, the general effect is so life-like as to make casual passers-by think that the figure is that of a living person. This is due to the combined 65 use of the glasses, the wax figure, the hair, and the clothing, and this effect is augmented by the background, the shadow box, and the lights. The said effect is furthermore enhanced by the provisions for arrangement of the head and the figure at different angles, so as to secure the best light-and-shade effects.

The entire apparatus is admirably suited 70 for the advertisement of different kinds of glasses, as the dressing of the figure and its angles of position can easily be varied according to the kind of glasses placed thereon.

The figure 6 may be of various lengths, either full length or bust-size, as shown in 75 the drawings, or otherwise.

Having thus described this invention, I hereby reserve the benefit of all changes in form, arrangement, order, or use of parts, as it is evident that many minor changes may 80 be made therein without departing from the spirit of this invention or the scope of the following claims.

I claim:

1. A shadow box for receiving a figure for advertising purposes, comprising a closed vertical rear wall, side, top, and bottom walls outwardly inclined from the edges of the rear wall, a short inwardly extended front flange projecting from the edges of the outwardly inclined side, top, and bottom inclined walls, and a block mounted on the bottom outwardly inclined wall and abutting against the inner face of the lower portion of the front flange to hold said block, whereby to support a figure within the box for advertising purposes.

2. A shadow box for receiving a figure for advertising purposes, comprising a closed vertical rear wall, side, top, and bot-

110

tom walls outwardly inclined from the edges of the rear wall, a short inwardly extended front flange projecting from the edges of the outwardly inclined side, top, and bottom inclined walls, a block mounted on the bottom outwardly inclined wall and abutting against the inner face of the lower portion of the front flange to hold said block, whereby to support a figure within the box for advertising purposes, and lamps located behind the front flange to direct light from the lamps against the outwardly inclined walls to deflect rays of light to a figure supported on the block.

15. 3. An advertising apparatus, comprising a box having outwardly inclined walls and

a continuous front inwardly extended flange, the interior surface of the box being lined with a soft material to form a background, a block supported on one of the outwardly inclined walls and abutting against the lower portion of the front flange to hold the block in place, a figure supported on the block, means for pivotally mounting the figure on the block, and lamps mounted on the inside of the front flange, the rays of light from the lamps being directed toward the figure by the inclined walls.

In testimony whereof I hereunto affix my signature.

ALBERT S. ALOE.
